ABSTRACT: An apparatus is provided for blocking a lens blank which has associated therewith reference means for cooperating in alignment of the blank prior to blocking. The apparatus includes means to accurately position the block immediately above the blank in a predetermined relationship to the prescribed optical and geometrical properties of the finished lens.

BLOCK HOLDER FOR OPHTHALMIC LENS BLANKS

CROSS-REFERENCE TO RELATED APPLICATION

This application is a continuation-in-part of U.S. Pat. application Ser. No. 675,967, filed Oct. 17, 1967, now U.S. Pat. No. 3,501,842 entitled METHOD AND APPARATUS FOR BLOCKING MULTIFOCAL LENS BLANKS.

BACKGROUND AND SUMMARY OF THE INVENTION

This invention relates to an improved method and apparatus for blocking lens blanks that have been either "marked-up" by the blocking technician or prferred by the manufacturer for purposes of accurately locating the optical and mechanical centers and the cylinder and horizontal axes of the finished lens. Standard prescription laboratory procedures may be employed for "marking-up"; and prferred lens blanks of the type that may be employed with this invention are further described in pending U.S. Pat. application Ser. No. 520,173, filed Jan. 12, 1966. Although this present invention is not limited to blocking multifocal lens blanks that have been prferred, but is usable with other blanks as well, the disclosure will be directed to that particular embodiment of blank.

Thus, in the manufacture of multifocal lenses having a reading segment thereon, the optical and mechanical centers and cylinder and horizontal axes must be accurately and precisely located in accordance with the particular prescription by the prescription shop. In this connection, the grinding and polishing operations are performed with reference to the optical center and cylinder axis. These operations are generally facilitated by the securing of a block on the lens blank which is indexed relative to these optical properties following a visual alignment procedure requiring the exercise of skill and patience and the expenditure of a considerable period of time. The mechanical center and horizontal axis must also be located on the lens blank, and these properties are then utilized in the shaping of the final edge of the lens according to the prescription. Either a suitable peripheral holding device or another block is secured to the blank after being accurately indexed relative to the stated geometrical properties following another tedious visual alignment procedure. When other lens blanks are to be blocked, "marking-up" and sighting techniques well known to the art may be employed.

It is, therefore, a principal object of this invention to provide a novel apparatus designed to quickly and efficiently block a lens blank by utilizing references which have been placed on the blank in a predetermined relationship.

Briefly stated, the multifocal lens blank of the type utilized with a specific embodiment of this invention is provided with references which are indexed relative to the bifocal or reading segment for purposes of accurately locating the optical and mechanical centers and the cylinder and horizontal axes of the finished lens. Exemplary edge referencing comprises a pair of spaced referenced flats milled into the peripheral edge of the lens blank with one flat extending in a substantially vertical direction at a predetermined distance from the center of the upper edge of the reading segment and the other reference flat extending in a substantially horizontal direction at a predetermined distance from the upper edge of the segment while being disposed at a predetermined angle relative thereto. The apparatus of the present invention utilizes these edge references to index a block in a predetermined relationship to the desired optical or physical properties of the lens according to the particular lens prescription. The block is then secured or cemented to the lens blank and is subsequently utilized to hold the blank during the grinding and polishing or edging operations.

Generally, the apparatus of the present invention comprises a frame having a surface for supporting the lens, the surface having a designated center thereon, means on the frame to engage the references of the lens to accurately position the lens

on the surface in relation to the designated center, and means for positioning a lens block immediately above the lens and accurately positioned in relation to the designated center.

Other objects and advantages will become apparent from the following detailed description and accompanying drawings.

BRIEF DESCRIPTION OF THE DRAWINGS

- 10 FIG. 1 is a front elevational view of a lens blank having edge reference flats ground or otherwise formed in the periphery;
 FIG. 2 is a perspective view of the blocking apparatus of the subject invention;
 FIG. 3 is a perspective view of a portion of the blocking apparatus showing the block holder positioned in the centering ring and adapted to receive an injection of bonding material;
 FIG. 4 is a top plan view of the blocking apparatus, the centering ring being shown in phantom lines;
 FIG. 5 is a sectional view of the blocking apparatus taken 20 along the line 5-5 of FIG. 4, but additionally showing the centering ring, block holder, and block in assembled relationship;
 FIG. 6 is a top plan view of the block holder;
 FIG. 7 is a sectional view taken along the line 7-7 of FIG. 6;
 FIG. 8 is a bottom plan view of the block holder;
 FIG. 9 is a top plan view of the lens block;
 FIG. 10 is a sectional view taken along the line 10-10 of FIG. 9; and
 FIG. 11 is a view similar to FIG. 7 but showing the lens block positioned in the holder.

DESCRIPTION OF THE PREFERRED EMBODIMENT

Referring to the drawings, the blocking apparatus of the subject invention is indicated generally at 10 and is designed to be utilized by a prescription shop for the purpose of blocking lens blanks and in accordance with the exemplary embodiment, the edge referenced lens blank 20 may be employed.

In the illustrated embodiment, the blank 20 includes a bifocal or reading segment 22 and edge referencing surfaces 24 and 26. The surface 24 consists of a substantially vertically extending reference flat or sector located at a known fixed horizontal distance "a," left or right, from the center 28 of the upper edge or segment line 30 of the segment 22. The surface 26 comprises a substantially horizontally extending reference flat or sector located at a known fixed vertical distance "b" from the segment line 30. This surface 26 is also accurately angled with respect to the segment line 30 and, in the illustrated embodiment, this angle is zero and the surface 26 is substantially parallel to the segment line 30. Further details of the lens blank 20, and in particular, details relating to its method of manufacture, may be obtained by reference to pending application Ser. No. 520,173.

The blocking apparatus 10 includes a frame having a surface 12 with a centering ring 14 mounted thereon. The centering ring 14 is positioned in parallel but spaced relation to the surface 12 and has a cylindrical opening 16 which opens to the surface 12. The cylindrical opening 16 defines a blocking cavity 18 and also a designated center on the surface 12 for the purposes hereinafter set forth.

The lens blank 20 is initially positioned on the surface 12 within the blocking cavity 18 as shown in the drawings. While in the illustrated embodiment the entire surface 12 as shown as being generally planar, it should be understood that the lens blank could be supported within the cavity 18 on other surfaces such as a circular ring or three points. The frame is provided with an adjustable height slide 32 having a straight abutment edge 34 which projects into the blocking cavity 18 and against which the reference flat 26 is adapted to abut. The slide 32 is adjustable mounted on the surface 12 and is provided with an index line 36 which is associated with a scale 38. The scale is suitably calibrated, such that when the index line 36 is at the "O" scale line, the vertical distance from the segment line 30 to the designated center in the cavity 18 is zero.

As the index line 36 is moved along the scale 38, which may be conveniently calibrated in millimeters, a corresponding distance will be traversed above or below the segment line 30.

The frame of the blocking apparatus 10 also mounts a pair of rotatable eccentric circular cams 40 and 42. The cam 40 is used with the right eye lens blank and the cam 42 is used with the left eye lens blank. Each cam partially projects into the blocking cavity 18 and, as shown, the reference flat 24 is adapted to abut the cam 40. Each cam is provided with a scale 44 which is associated with an index line 46 on the surface 12. When the cam 40 is rotated so that the zero scale line is opposite index line 46, the horizontal distance from the center of the segment line 30 to the designated center in the cavity 18 is zero. As the cam 40 is rotated causing a different line on the scale 44 to be opposite the index line 46, the distance from the center of the segment line 30 to the designated center is displaced a corresponding amount. In this manner, the intended optical center and/or mechanical center positions may be mechanically located with respect to the segment 22 by simply employing the edge referenced flats 24 and 26 on the blank 20 and the adjustable height slide 32 and the eccentric circular cam 40.

When the blank 20 is positioned with respect to the height slide 32 and cam 40 according to prescription, the lens block 50 is placed inside the block holder 52. The block holder 52 comprises a lower circular ring 54 and an upper handle 56 which is suitably connected across the top of the ring. A gasket 58 is positioned in the internal opening of the ring 54 which has a downwardly extending locating edge 60. The outer circumference of structure ring 54 includes a conical surface portion 62 and a portion 64 which is a segment of a sphere, the center of which closely coincides with the axis of the blocking cavity 18 and with the upper surface of the lens blank 20 when the device is fully assembled as hereinafter further described. The block 50 which may be of any conventional configuration has an outer diameter which closely corresponds to the internal diameter of the gasket 58. The block 50 may thereby be positioned in the holder 52 as seen in FIG. 11 to form a unitary structure.

The assembly of the block 50 and block holder 52 is then lowered into the blocking cavity 18 as illustrated in FIG. 5. The block holder 52 is adapted to cause the center of the lens block 50 to correspond to the designated center of the blocking cavity 18 and thereby also with the center of the segment line 30 when the index lines 36 and 46 are at the zero scale lines on scales 38 and 44. As the prescription dimensions are introduced by means of the slide 32 and cam 40, the center of the block 50 will be offset from the center of the segment line 30 a corresponding amount. The portion 64 on the periphery of the block holder 52 has substantially the same diameter as the wall of the cylindrical opening 16, thus allowing the holder 52 to tip or pivot about its center within the blocking cavity 18. This ability to pivot within the blocking cavity 18 allows the holder 52 to maintain a close fit with the inner diameter of the opening 16 and to maintain the locating edge 60 properly seated upon the lens blank 20, regardless of the amount of height adjustment and decentration of the blank 20 introduced by the height slide 32 and centering cam 40. The holder 52 is also vertically adjustable to accept lens blanks of various thicknesses.

One block 50 may be employed for producing the prescribed optical surface on the lens blank 20, and another block of appropriate form may then be employed for the purpose of performing the final edging operation according to the prescription on the blank 20. For the surfacing operations, the optical center would be located by proper settings of the slide 32 and cam 40. For the final edging operation the mechanical center would similarly be located by means of the slide 32 and cam 40.

The block holder 52 is provided with an angularly divided scale 66 on the conical surface 62. The scale 66 is used to determine the prescribed cylinder or horizontal axis alignment in relation to a designated direction within the blocking cavity

18, which in the illustrated embodiment corresponds to the direction of the segment line 30 as well as the direction of the abutment edge 34. The scale 66 is suitably calibrated in degrees and is adapted to be compared with the index 68 on the upper surface of the centering ring 14.

The prescribed cylinder or horizontal axis alignment is introduced by a number of cooperating elements in the holder 52 and block 50. In accordance with the illustrated example, the holder 52 includes a pair of downwardly extending spring loaded pins 70 and 72 which are mounted in the upper handle 56. A plane passing through the axes of these pins will pass through the center of the holder 52 and the axis of the block 50. The block 50 includes a complementary pair of recesses 74 and 76 for receiving the ends of the pins 70 and 72, respectively. These recesses 74 and 76 are conveniently provided by means of the plug inserts 78 and 80. The axes of the recesses define a plane that will be seen to coincide with the plane defined by the axes of the pins 70 and 72 when the block 50 is inserted into the holder 52 and properly oriented. Under these circumstances, rotation of the block holder 52 will cause a corresponding rotation of the block 50 to thereby introduce the prescribed axis alignment.

In accordance with the illustrated example of the block 50, a hollowed cavity 82 is provided at the bottom surface of the block 50 for the reception of a suitable adhesive for securing the block to the blank 20. The bonding material may be introduced into the cavity 82 through the pouring holes 84 and 86 which are provided in the block 50. The adhesive may be injected into one of the two holes in the block from a suitable syringe 90 as shown in FIG. 3. The adhesive may be pitch or a low melting point alloy, such as an antimony lead compound, which hardens rapidly following pouring.

The lower surface of the locating edge 60 of the holder 52 rests upon the blank 20 and serves to position the block 50 suitably with respect to the lens blank. The edge 60 is highly polished and thus further serves to assure the retention of the bonding material between the block 50 and the blank 20 by providing an unbroken circular edge of contact between the two.

Thus, in this manner, a properly and accurately positioned block is secured on a blank for purposes of producing the prescribed optical properties on the lens blank. Another block 45 positioned in a similar manner may subsequently be applied following removal of the block 50 for positioning the blank during the final edging operation. This subsequently applied block may then be employed to produce the desired final geometrical configuration of the finished lens.

50 It will now be appreciated that the prescription shop need only utilize the referencing means provided by the manufacturer to automatically and accurately locate the optical and mechanical centers and cylinder and horizontal axes on the blank in producing the optical and geometrical properties dictated by the prescription. The error prone visual alignment procedures formerly employed are no longer required.

Inasmuch as the present invention is usable with all forms of ophthalmic blanks referenced or not, a brief explanation will be given to blocking certain of these blanks. In order to render the block holder 52-centering ring 14 device workable with nonreferenced blanks, the ultimate optical center and horizontal axis may be portrayed by paint marks on the finished surface of the lens blank. These marks can then be aligned with the center and horizontal (zero degrees) axis of the block holder 52 and ring 14. Standard lab procedure for the "marking-up" of the lens blanks for alignment during blocking is to mark the finished surface of the blank with paint. After the lens blank has been marked up, it would be laid upon surface 12 within the ring 14. As a means for placing the paint marks in the exact alignment required before the block holder 52 is lowered into place for blocking, an optical viewer with target may be employed. The target of this optical viewer would be superimposed for alignment against the paint marks.

Alternatively, a simpler alignment means may be provided in the form of a cross which is formed by engraving or painting on surface 12, and centered and horizontally aligned with respect to the ring 14. In use, the operator would view the target on surface 12 through the lens blank, moving the blank around until, as he sighted vertically downwards, the paint marks on the lens blank and the cross were superimposed. This visual means of alignment by sighting through the lens blank against a target has been widely used for blocking purposes for many years.

Although a somewhat preferred embodiment of this invention has been disclosed and described in detail herein, it should be understood that this invention is in no sense limited thereby and its scope is to be determined by that of the appended claims.

I claim:

1. In a blocking apparatus wherein a preformed cylindrical block is joined to a lens blank in predetermined relationship to the prescribed optical and geometrical properties of the finished lens, said apparatus comprising:

a frame having means for supporting the lens blank;
a circular ring for surrounding said block and having means for retaining said block therein, said ring having a spherical segment associated therewith;
means fixedly mounted on said frame for laterally supporting said ring immediately above said lens blank, said lateral support means being in engagement with said spherical segment for cooperating in accurately positioning said ring when tilted into engagement with the convex surface of said lens blank;

and means for adjusting the relative rotational positioning between said block and said frame when said block is retained in said ring.

2. The blocking apparatus as defined in claim 1 wherein said means for adjusting the relative rotational positioning comprises integrating means between said circular ring and said block whereby relative rotation therebetween is precluded.

3. The blocking apparatus as defined in claim 2 wherein the said means for retaining said block within said ring comprises a frictional engagement between the outer periphery of said block and at least a portion of the internal diameter of said ring.

4. The blocking apparatus as defined in claim 3 wherein said ring further includes a cylindrical gasket having a downwardly extending locating edge adapted to engage the lens blank when said ring is positioned in said lateral support means.

5. The blocking apparatus as defined in claim 4 further including indicia on said lateral support means to indicate the relative rotational position of said ring.

6. The blocking apparatus as defined in claim 1 further including means for accurately positioning said lens blank on said supporting means in a predetermined relationship with respect to said lateral support means.

7. The blocking apparatus as defined in claim 6 wherein said lateral support means comprises a centering member defining a cylindrical opening, said cylindrical opening having a diameter substantially the same as the outer diameter of said ring such that said centering member rotatably encloses said ring.

8. Blocking apparatus for joining a performed lens block to a lens blank in predetermined relationship to the prescribed optical and geometrical properties of the finished lens, said blocking apparatus comprising:

a frame having means for supporting a lens blank;
a lens block to which said lens blank is to be joined;
a circular ring for supporting said lens block, said circular ring including means for frictionally retaining said block therein;

a centering member fixedly mounted to said frame for laterally supporting said circular ring immediately above said lens blank, said centering member defining a cylindrical opening having a diameter substantially the same as the outer diameter of said circular ring for rotatably enclosing said circular ring; and
means for adjusting the relative rotational positioning between said circular ring together with said lens block and said centering member when said lens block is retained in said circular ring.

9. Blocking apparatus as defined in claim 8 wherein said means for adjusting the relative rotational positioning comprises interengaging means between said circular ring and said block for precluding relative rotation therebetween.

10. Blocking apparatus as defined in claim 9 wherein said centering member includes indicia for indicating the relative rotational positioning between said ring together with said lens block and said centering member.
